UNITED STATES PATENT OFFICE.

CHARLES MANSHEL, OF NEWARK, NEW JERSEY.

DESIGN FOR A SAFETY PAPER FOR TICKETS OR CARDS.

Application filed June 28, 1922. Serial No. 2,855. Term of patent 14 years.

To all whom it may concern:

Be it known that I, CHARLES MANSHEL, a citizen of the United States, residing at Newark, in the county of Essex and State of New Jersey, have invented a new, original, and ornamental Design for a Safety Paper for Tickets or Cards, of which the following is a specification, reference being had to the accompanying drawing, forming a part thereof.

The drawing shows a plan view of a portion of a safety paper for a ticket or card illustrating my new design.

I claim:—

The ornamental design for a safety paper for tickets or cards, as shown.

CHARLES MANSHEL.
